UNITED STATES PATENT OFFICE.

JULIUS PEGEL, OF PHILADELPHIA, PENNSYLVANIA.

DESIGN FOR A RUG.

SPECIFICATION forming part of Design No. 19,493, dated December 17, 1889.

Application filed November 23, 1889. Serial No. 331,376. Term of patent 3½ years.

To all whom it may concern:

Be it known that I, JULIUS PEGEL, a citizen of the United States, and a resident of Philadelphia, Pennsylvania, have invented a 5 Design for Rugs, of which the following is a description, reference being had to the accompanying photographic illustration, making part hereof.

The illustration shows only half of the rug, 10 the other half being a duplicate thereof.

A is the middle panel, representing an oblong angular figure pointed at either end B. Within this panel is a center piece C of general diamond shape, each end terminating in 15 a pointed cap D. This center piece is surrounded by a fretted line E, following the general form of the center piece, in the middle of which latter is ornamented by fanciful figures F.

G G are corner pieces, about square in general outline, with fretted work H about the edges and center pieces I I. The panel A also has fret-work outer edges.

J J J are fanciful ornamental figures on the groundwork between the panel and the border K.

L is a small middle ornamental piece, generally resembling the corner pieces G G.

What I claim is—

The design for a rug, as shown.

In witness that the above is my invention I have hereunto set my hand.

JULIUS PEGEL.
